TONGUE FOR SHUTTLE BOXES IN WEAVING LOOMS

Jaime Picanol, Casa Pairal Catalunya,
Zillebeke-lez-Ypres, Belgium

Filed Nov. 1, 1956, Ser. No. 619,787

Claims priority, application Belgium Dec. 17, 1955

4 Claims. (Cl. 139—185)

This invention pertains to weaving looms. As is well known, it is an indispensable condition for the correct operation of a weaving loom, that the shuttle be guided throughout its course by a perfectly smooth and even guiding surface. In other words, the shuttle must be so guided as to meet no irregularity or disturbing influence as it moves across the loom. This condition is particularly necessary, when the loom is operated at higher speeds. In fact, such irregularities may give rise, especially at high operating speeds, to friction effects, changes of movement and generally speaking to all kinds of disturbing influences endangering not only the normal operation of the looms but also the making of flawless fabrics. However, the shuttle, right from the start, while it still is in the shuttle box, has, due to the action of the picker motion, the tendency to strike against the guiding wall formed by the floating dagger or swell and the rocking tongue. In prior art constructions, the latter may cause a discontinuity in the lateral guide surface of the shuttle. It follows that, the normal movement of the shuttle is disturbed at the very start, particularly if the loom is operated at high speed, whereby the correct operation of the loom is imperilled. An object of the present invention is to eliminate these drawbacks of prior art constructions.

The invention relates to a certain arrangement of the rocking tongue and to means for adjusting the position of said tongue in such a way that, when said tongue is in its normal position, its front face lies exactly in the plane of the polished shuttle-guiding surfaces and of the reed and is firmly maintained in this position, so that a perfectly even and continuous lateral guiding surface is provided. For this purpose, the rocking tongue is so fitted and shaped as to hinge on a suitably disposed pivot—as will be described in greater detail hereinafter. Furthermore, the tongue is provided with means permitting easy adjustment of its position, e.g. in the shape of a cam or eccentric bearing against a corresponding part of said tongue, the latter pressing against two points one of which is fixed and the other movable or adjustable, in such manner that said tongue may be secured at any moment in the correct position.

According to the invention, the pivot axis of the tongue is disposed behind and—approximately—on a level with the corresponding end of the front face aligned with the shuttle-guiding surfaces, in such manner that, when the returning shuttle contacts said rocking tongue, the latter will not exert any detrimental resistance upon said shuttle.

This particular disposition as well as other features of the invention will be described in greater detail hereinafter with reference to the accompanying drawings, wherein:

Figure 1 is a diagrammatic top view of the main elements of a weaving loom showing to locate the position of the improved tongue structure according to the invention;

2

Figures 2 and 3 show the rocking tongue in two characteristic positions;

Figure 4 shows diagrammatically the mechanism controlled by said tongue and

5 Figure 5 is a top view of a practical embodiment of the rocking tongue according to the invention. The rocking tongue 1 has approximately the shape of an L, the horizontal leg being so arranged as to lie securely and exactly in the plane of the shuttle-guiding surfaces 9 and the reeds 10, whenever the shuttle is in the shuttle box, whereas the vertical leg of said L-shaped tongue is mounted, at its free end, on a pivot 2. As is well known, the purpose of the shuttle-guiding surfaces 9 is to provide a perfect alignment between the reeds 10 and the rear face of the shuttle boxes located upon the right and the left of the loom, beyond each surface 9. The surfaces 9 are perfectly plane and along with the reeds and adjacent surfaces of the shuttle boxes they provide a perfectly continuous surface; thus they serve as connection pieces between the reeds and the shuttle boxes to assure continuous guiding of the shuttle from one end to the other end of the loom. Obviously the real shape of the tongue corresponds only approximately to the letter L, the latter relating particularly to the relative position of the front face of the rocking tongue requiring to be adjusted in the plane of the shuttle-guiding surfaces, and the lateral wall adjacent to said front face of said rocking tongue, and connecting said front face with said pivot 2. Consequently the pivoting center of the rocking tongue is—at least approximately—disposed on a line perpendicular to the shuttle race and extending through the point 3 of the front face of the rocking tongue first met by the shuttle on its return into the shuttle box. This location of the pivot 2 with respect to the front face of the rocking tongue, more particularly with respect to the forward edge 3 of said front face, is an essential feature of the present invention, since as a result thereof the manner in which the rocking tongue is acted upon by the returning shuttle is particularly effective, the latter establishing smoothly and progressively a contact with the former, in spite of the high speed of said shuttle.

As a means for correctly adjusting the position adopted by the rocking tongue when the shuttle is in the shuttle box, there is provided, according to the invention, a cam or eccentric 4 acting as a stop and as a brake for braking the movement of the returning shuttle. In order to alter the position of the line of contact between the eccentric 4 and the rocking tongue it is merely necessary to rotate the eccentric 4 about its axis, whereby the retracted position of the rocking tongue may be adjusted with great precision. The rocking tongue acts in the usual way on the press button 5, the latter being connected by a lever 6 with the stop rod nose 7, this mechanism being mounted on the batten 8 in the usual way (Figure 1).

Due to this arrangement, a lasting adjustment of the position of the rocking tongue may be effected in a very simple manner, while the latter, without losing anything in efficiency as a braking element for the shuttle on its return into the shuttle box, is so constructed that it will not disturb in any way whatsoever the movement of the shuttle, particularly during the start of the latter, when the rocking tongue is firmly pressed against its pivot 2 and also against the eccentric stop element 4.

It is obvious that the eccentric device may be replaced by any other type of stop element, so long as such element permits shifting the position of its contact line or contact surface with the rocking tongue, for the purpose of adjusting the retracted position of the latter. Similarly many modifications in the detailed shape of the rocking tongue may be made, provided its pivot point is

disposed on a line perpendicular to the shuttle race and passing through the forward edge of the tongue, i.e. the point first met by the shuttle on its way into the shuttle box.

It is also evident that the described arrangement of the rocking tongue might be used independently of the means for adjusting the position of said tongue, and vice versa.

What I claim is:

1. In a weaving loom having a batten, a shuttle race mounted on said batten; a shuttle box at either side of said batten each at an end of said shuttle race; means for projecting a shuttle along said shuttle race from one of said shuttle boxes into the other and vice versa; a tongue, means pivotally supporting said tongue sideways at the entrance of each of said shuttle boxes so as to cause said tongue to partially project into the path of said shuttle when the latter is entering into said shuttle box and to brake the speed of said shuttle while yielding sideways thereto, while said shuttle is penetrating into said shuttle box, the pivoting centre of said tongue being disposed on a line substantially perpendicular to said shuttle race and extending through that point of said tongue which will be first met by the shuttle, when the latter enters into said shuttle box.

2. In a weaving loom having a batten, a reed mounted on said batten, shuttle-guiding surfaces on said batten at either side of said reed and disposed in a plane with one face of said reed, a shuttle race mounted on said batten in front of said plane of said shuttle-guiding surfaces and said reed, a shuttle box at each end of said shuttle race, means for projecting a shuttle along said shuttle race from one of said shuttle boxes into the other and vice versa, a tongue pivotally mounted sideways at the entrance of each of said shuttle boxes and disposed so as to partially project into the path of said shuttle when the latter enters into said shuttle box and to brake the speed of said shuttle while yielding sideways thereto while said shuttle is penetrating into said shuttle box, said tongue having roughly the shape of an L and comprising a base part with a substantially flat outer surface, and an upright part substantially at right angles with said flat outer surface and joining said base part at such point as will be first met by the shuttle when the latter

enters into said shuttle box, said tongue being pivoted on a fixed part of said batten at a point adjacent said upright part of said tongue, and means for arresting the lateral yielding movement of said tongue in a position whereby said outer face of said base part is in a plane with said shuttle-guiding surfaces and said reed.

3. In a weaving loom having a batten, a reed mounted on said batten, shuttle-guiding surfaces on said batten at either side of said reed and disposed in a plane with one face of said reed, a shuttle race mounted on said batten in front of said plane of said shuttle-guiding surfaces and said reed, a shuttle box at each end of said shuttle race, means for projecting a shuttle along said shuttle race from one of said shuttle boxes into the other and vice versa; a tongue pivotally mounted sideways at the entrance of each of said shuttle boxes and disposed so as to partially project into the path of said shuttle when the latter is entering into said shuttle box, and to brake the speed of said shuttle while yielding sideways thereto while said shuttle is penetrating into said shuttle box; the pivoting centre of said tongue being disposed on a line substantially perpendicular to said shuttle race and going through such point of said tongue as will be first met by the shuttle when the latter enters into said shuttle box, adjustable means for arresting the lateral yielding movement of said tongue, whereby the limit position of said tongue is precisely determined, said stop means being such as to permit positional adjustment of its contact area with said tongue, so as to permit bringing the outer face of said tongue into a plane with said shuttle-guiding surfaces and said reed.

4. Weaving loom as claimed in claim 3, wherein said arresting means is a rotatably mounted cam device so shaped and so mounted that, by rotating said cam device about its axis, the line of contact offered to said tongue is shifted.
